UNITED STATES PATENT OFFICE.

OTTO RANGNOW, OF PHILADELPHIA, PENNSYLVANIA.

DOWEL-PIN AND FASTENER FOR TRUNKS.

SPECIFICATION forming part of Letters Patent No. 761,322, dated May 31, 1904.

Application filed February 29, 1904. Serial No. 195,801. (No model.)

To all whom it may concern:

Be it known that I, OTTO RANGNOW, a citizen of the United States, residing at Philadelphia, in the county of Philadelphia and State 5 of Pennsylvania, have invented certain new and useful Improvements in Dowel-Pins and Fasteners for Trunks, of which the following is a specification.

My invention relates to an improved dowel-pin and fastener for trunks, and relates to that 10 class of dowel-pins in which the same are divided into two members, one of said members being carried by the lid of the trunk and having formed thereon a pin, and upon the other 15 member, which is carried by the body of the trunk, is formed a socket adapted to receive the said dowel-pin and having therein mechanism for fastening said dowel-pin.

The object of my invention is to construct 20 a dowel-pin and fastener which will automatically lock when the parts are brought together and which does not require the action of a spring to hold the said parts locked.

A further object of my invention is to provide 25 a means of unlocking the fastening mechanism and of causing the members to spring apart and remain unlocked until the lid of the trunk is lifted.

Referring to the drawings, Figure 1 is a 30 front elevation of a trunk, showing my improved dowel-pin and fastener applied thereto. Fig. 2 is a vertical sectional view as on line 2 2, Fig. 1, on a larger scale. Fig. 3 is a similar view showing the parts in a different position. Fig. 4 is a sectional view on line 4 4, Fig. 2. Fig. 5 is a perspective view of one of the parts detached.

In the drawings, A refers to the lid of a trunk, and B the body of a trunk. To the 40 lid A is attached the upper member C of the dowel-pin, carrying a dowel-pin C', having formed on its lower end a shoulder c, projecting rearwardly or toward the trunk. A handle or lift C² also forms a part of the upper member C. The upper member C is attached to the lid of the trunk by means of rivets a a and a' a'. The rivets a a pass through the lid of the trunk, while the rivets a' a' only pass through the valance-strip A², which is secured to the lid by rivets a³. The object of

this is to hold the dowel-pin in a vertical line and to give the lower end of the dowel-pin sufficient flexibility to allow it to be forced over a projection in the fastening mechanism, as described later. The lower member D, which is 55 secured to the body of the trunk, has an enlarged portion d, forming a socket to receive the dowel-pin C'. As shown in Fig. 4, said lower member D is provided with flanges D² on its outer edges, which form a recess adapted to receive a plate E. Apertures are formed in the said plate E, which align with apertures in the lower member to receive rivets f, by which the plate E and the lower member D are rigidly secured to the body of the trunk. 60 Within the socket formed in the enlarged portion d is a web d', having projecting therefrom a pin d², which passes through the plate E and holds said plate and the lower member D together. On the said plate E is a struck-up portion E', which forms a projection E², which projects forwardly to engage the shoulder c on the dowel-pin C'. The said struck-up portion E' forms a cam-surface E³, which forces the pin C' out of the vertical line when 65 entering the said socket. A spring G is held within the said socket by means of said pin d². This spring is only in action when the dowel-pin C' is entering or leaving the socket, as shown in Fig. 3. When the dowel-pin C' has 70 dropped into place over the projection E², as shown in Fig. 2, the spring G will be released and will not exert any pressure against the said dowel-pins, which will be held in engagement with the said projection by means of the 75 rivets and valance-strip carried by the lid A. Should the valance-strip A² fail to hold the dowel-pin C' in its proper vertical position, the said spring G will prevent it from becoming disengaged from the projection E². A latch 80 F is pivoted on the said pin d². The lower end F' of said latch has a depression formed therein for the fingers, and its opposite end F² projects into the center of the socket, so as to engage the dowel-pin C'. 85

When it is desired to open the trunk, the lower end of the latch F is forced in, which causes its other end, F², to bear against the dowel-pin C' and force it back against the action of the spring G until the shoulder c is 90 95 100

drawn out of engagement with the projection E², as shown in Fig. 3, when it will be forced upwardly by the action of the spring G and the latch F to the position shown in dotted lines in Fig. 3. The lower end of the dowel-pin C' is provided with curved surfaces which facilitate the movement of the dowel-pin C' into and out of engagement with the different parts.

10 The lower member D is provided with downwardly-projecting walls H and H' to protect the latch from any accidental blow. It will be seen that in my improved dowel-pin and fastener the parts will remain locked 15 without the action of any spring. The spring is only in action when the dowel-pin is being forced into place or being forced out of engagement with the projection by means of the latch, and therefore it will not lose its 20 vitality as it would if under constant tension.

Having thus described my invention, I claim and desire to secure by Letters Patent—

1. The combination of an upper member carrying a dowel-pin with a shoulder formed thereon, a lower member having a projection to engage said dowel-pin, a latch to disengage said dowel-pin, and a spring adapted to force the said dowel-pin from said lower member, substantially as described.

2. The combination of an upper member, a 30 dowel-pin carried by the same, a shoulder formed on said dowel-pin, a lower member having a socket formed therein, a plate having a projection formed thereon, a pin securing said plate to said lower member, walls 35 projecting downwardly from said lower member, a latch pivoted on the latter pin and a spring secured in said lower member, substantially as described.

3. The combination of an upper member, 40 carrying a dowel-pin having a shoulder formed thereon projecting rearwardly, a lower member having a socket formed therein, a plate to complete said socket, said plate having a projection extending forwardly, a latch to disengage said dowel-pin from said projection, and a spring to force said dowel-pin upwardly 45 when acted upon by said latch and also to prevent the accidental disengagement of said dowel-pin and said projection, substantially 50 as described.

In testimony whereof I affix my signature in presence of two witnesses.

OTTO RANGNOW.
